UNITED STATES PATENT OFFICE

110,528

DESIGN FOR A VALVE REGULATOR

Frank E. Rice, Detroit, Mich., assignor to American Tap-Bush Company, Detroit, Mich., a corporation of Delaware

Application April 22, 1938, Serial No. 76,696

Term of patent 14 years

To all whom it may concern:

Be it known that I, Frank E. Rice, a citizen of the United States and a resident of the city of Detroit, in the county of Wayne and State of Michigan, have invented a new, original, and ornamental Design for a Valve Regulator, of which the following is a specification, reference being had to the accompanying drawing forming a part thereof.

On the drawing:

Figure 1 is a top plan view of the valve regulator showing my new design;

Figure 2 is a side elevational view thereof.

I claim:

The ornamental design for a valve regulator as shown.

FRANK E. RICE.
